US0D1047363S

(12) United States Design Patent (10) Patent No.: US D1,047,363 S
(45) Date of Patent:  Oct. 22, 2024

(54) SHOE

(71) Applicant: NIKE, Inc., Beaverton, OR (US)

(72) Inventors: Benjamin Nethongkome, Beaverton, OR (US); Nick Matteo, Portland, OR (US); Mary A. Pengelly, London (GB)

(73) Assignee: NIKE, Inc., Beaverton, OR (US)

() Term: 15 Years

(21) Appl. No.: 29/922,385

(22) Filed: Dec. 21, 2023

(51) LOC (14) Cl. 02-04

(52) U.S. Cl.

USPC D2/972

(58) Field of Classification Search

CLAIM

The ornamental design for a shoe as shown and described.

DESCRIPTION

FIG. 1 is a side view of a shoe showing our new design; FIG. 2 is a rear perspective view thereof;

FIG. 3 is a rear view thereof;

FIG. 4 is an opposite side rear perspective view thereof; and,

FIG. 5 is an opposite side view thereof.

The broken lines immediately adjacent to the photographic area define the bounds of the claimed design and form no part thereof. The broken line showing of the square shaped area forms no part of the claimed design. The broken lines depicting the remainder of the shoe form no part of the claimed design.

1 Claim, 5 Drawing Sheets
